(57) **CLAIM**

The ornamental design for a welding gun, as shown and described.

DESCRIPTION

FIG. 1 is a perspective view of a welding gun showing our new design in accordance with a first embodiment of the invention;

FIGS. 2–3 are side views thereof;

FIG. 4 is a top view thereof;

FIG. 5 is a bottom view thereof;

FIG. 6 is a front view thereof;

FIG. 7 is a rear view thereof;

FIG. 8 is a perspective view of a welding gun showing our new design in accordance with a second embodiment of the invention;

FIGS. 9–10 are side views of the welding gun as shown in FIG. 8;

FIG. 11 is a top view of the welding gun as shown in FIG. 8;

FIG. 12 is a bottom view of the welding gun as shown in FIG. 8;

FIG. 13 is a front view of the welding gun as shown in FIG. 8; and,

FIG. 14 is a rear view of the welding gun as shown in FIG. 8.

Phantom lining, where utilized, is for illustrative purposes only and does not limit or form any part of the claimed design.

1 Claim, 8 Drawing Sheets
